John R. Schmidgall, 5628 N. Rosemead Blvd.,
Temple City, Calif.

Filed Aug. 4, 1965, Ser. No. 86,435

Term of patent 14 years

(Cl. D1—12)

FIG. 1.

FIG. 2.

FIG. 3.

FIG. 4.

FIG. 5.

FIGURE 4 is a perspective view of a modified form of the holder for signs, nameplates, or the like shown in FIGURES 1 through 3.

The dominant features of my design reside in the portions shown in full lines, the broken line showing of indicia being omitted from FIGURE 4 for convenience of illustration.

I claim:

The ornamental design for a holder for signs, nameplates, or the like, as shown and described.
